UNITED STATES PATENT OFFICE.

THOMAS NORRIS McNISH, OF KEARNEY, NEW JERSEY, ASSIGNOR TO THE PEELLE COMPANY, OF BROOKLYN, NEW YORK, A CORPORATION OF NEW YORK.

CONTROLLING MECHANISM FOR ELEVATOR-CARS.

1,356,994.

Specification of Letters Patent. Patented Oct. 26, 1920.

Application filed May 24, 1918. Serial No. 236,338.

To all whom it may concern:

Be it known that I, THOMAS NORRIS McNISH, a citizen of the United States, residing at Kearney, in the county of Hudson and State of New Jersey, have invented 5 certain new and useful Improvements in Controlling Mechanisms for Elevator-Cars, of which the following is a specification, reference being had therein to the accompanying drawings, which form a part thereof.

My invention relates to controlling mechanisms for elevator cars and more particularly to a mechanism actuated by the opening and closing of the doors of the elevator shaft, in a manner to permit power to be applied to the car only when all of the doors of a shaft are closed.

Heretofore it has been a common practice to provide in connection with elevator doors, what is known as an electrical or mechanical interlock, the purpose of which was to prevent the starting of a car from any floor, so long as the door at that floor 25 was open, and until the door was completely closed, each door in the shaft being equipped with this mechanism and a more or less complicated wiring system being required.

30 By means of a controlling mechanism made in accordance with my invention, I am enabled to use a single circuit-controller which may be arranged in the penthouse, or some other point inaccessible to the operator of the car, said controller being mechanically connected to every door in a shaft, so that the opening of any door in the shaft will cut off power from, or prevent the application of power to the elevator car. This mechanism is entirely independent of the lock upon the door and since, ordinarily, elevator doors are so constructed as to be incapable of being opened except from within the elevator shaft, it is 45 apparent that the power can be cut off from the car only when the car is at a door-opening of a floor.

To make a mechanism made in accordance with my invention, effective in use, it 50 is so constructed that the power will be cut off from the car substantially simultaneously with the initial opening of the door, and will become effective to close the circuit or otherwise release the controller

within the car, only when the door is substantially closed. 55

The controlling mechanism is entirely automatic, the actuating means therefore being so connected with the various doors of a shaft as to permit the opening and closing of any door without disturbing or affecting any other door in the shaft. Said actuating means is so constructed and arranged as to be capable of use with any type of door, whether of the vertically sliding, laterally sliding, or hinge type, and it may be as readily applied to a vertically sliding door of the truckable type or of a telescoping type, the mode of operation of the controlling mechanism being substantially identical, irrespective of the type of door to which it is applied. Furthermore, it may be applied to any of the well known types of elevator systems, irrespective of whether it be electric or hydraulic, or whether the controller for the car be an ordinary resistance box or whether it be a shipper cable. 70

The main object of the invention is to provide a controlling mechanism of the type to which my invention relates, wherein the controller for the car will be made inoperative by a single electrically actuated device, common to all of the doors in a shaft and so constructed and arranged that the opening of any door will make said controller for the car inoperative, and so maintain it until the door has been fully closed, so that a mechanical lock carried by the door must operate before power can be applied to the car. 80

The invention consists primarily in a controlling mechanism for elevator cars, embodying therein a controller operative from within a car, and means to prevent said controller being made operative to apply power to the car, comprising an electric circuit including therein a plurality of electric contacts, one of which is adapted to have movement in relation to the other, a movable member adapted to actuate said movable contact member, actuating means for said movable member extending adjacent all of the doors of a shaft, and means carried by said actuating means adapted by engagement with said doors respectively, to impart movement to said movable member with the opening and closing of any door in 95 100 105

a shaft; and in such other novel features of construction and combination of parts, as are hereinafter set forth and described, and more particularly pointed out in the 5 claims hereto appended.

Referring to the drawings:—

Figure 1 is a fragmentary portion of an elevator shaft showing two doors of the truckable type, and having a controlling 10 mechanism made in accordance with my invention, applied thereto;

Fig. 2 is a detail view upon a larger scale of the make and break mechanism and the movable member actuating same;

Fig. 3 is a detail view of said mechanism modified to adapt it to a controlling system 15 for elevators employing a solenoid;

Fig. 4 is a view of a portion of an elevator shaft having therein doors of the telescoping 20 type with my invention applied thereto;

Fig. 5 is a similar view showing the invention applied to laterally sliding doors; and

Figs. 6 and 7 are respectively a view of a 25 portion of an elevator shaft employing double swinging doors and a cross-sectional view thereof upon a larger scale, a controlling mechanism made in accordance with my invention being shown in connection 30 therewith.

Like letters refer to like parts throughout the several views.

In Fig. 1 of the drawings, I have shown an embodiment of the invention as applied to 35 a type of door known as a truckable door, consisting of two door sections, *a* and *b*, arranged at each door opening in the elevator shaft, said sections moving vertically in the same plane, but in opposite directions, 40 when opening and closing the door. The said sections are provided with a suitable lock *c*, operative when the doors are in the closed position. The two sections are connected by means of suitably mounted cables 45 *d*, insuring this simultaneous movement.

The section *b* is provided with a laterally extending hanger bar *b'*, to which the cables *d* are connected. The doors *a* and *b* are mounted upon suitable rails or guides in 50 the usual and well known manner.

Ordinarily a series of such doors are mounted in an elevator shaft, the door openings being positioned one above the other, so that the various hanger bars *b'* are all 55 in the same vertical plane and extend parallel with each other. This general construction is old and well known in this art, and merely exemplifies one type of door in connection with which my invention may be 60 employed.

To place the power for the elevator car under the control of the elevator doors, I include in the circuit to the controller *E* upon the car, a make and break mechanism, 65 including a plurality of coöperating electric

contacts, one of which is spring actuated and adapted to have movement in relation to the others, and associated therewith, means adapted to be actuated by a connection having an operative relation to one of the sections of each door in a shaft, so that when the door is closed the circuit to the car will be closed, and when the door is open the circuit will be open, thus preventing the operator from starting the car until the door 70 is again closed.

This mechanism in the form of the invention shown in Figs. 1 and 2, comprises a bridge switch consisting of fixed contacts *e* and *e'* and a movable contact *f* slidably mounted upon a plunger *f'*, having thereon a collar *f''* against which a spring *f'''* acts, the other end of said spring acting upon the base *g'* of insulating material mounted in the switch box *g*. Mounted adjacent the switch 80 box *g* and above the plunger *f'* is a sliding weight *h* constituting the movable member for actuating the contact member *f*, said weight *h* being connected by means of the flexible strip or cable *i* having impact blocks 85 *i'* thereon, with the several hanger bars *b'*. The said hanger bars are ordinarily made of angle iron, the strip or cable *i* passing through an opening in one flange of said bar, and having a free sliding fit therein, so that as the opening of one door imparts movement to the weight *h* through said strip or cable *i*, the blocks *i'* associated with the hanger bars of other doors, merely move away from the operative relation thereto, so 90 that the actuation of any door does not interfere with other doors in the shaft. 95

To insure the desired movement of the strip or cable *i*, I provide the lower end thereof with a weight *j* which will always 100 hold said strip taut, while being of insufficient weight to overbalance the weight *h*.

The contacts *e*—*e'* and the controller *E* are included in the circuit supplying power to the car by means of the conductor wires 110 *k*—*k'*.

In Fig. 3 of the drawings, I have illustrated the invention as applied to a type of elevator employing a shipper cable, the sole difference in structure between this form of the invention and that shown in Figs. 1 and 2 being a reversal of the relation of the contacts *e*, *e'* and *f*, so that the circuit instead of being normally closed, will be normally open. In this form of the invention, the 115 terminal wires *k*—*k'* instead of leading to the controller in the elevator car, lead to the terminals of the solenoid *m*, which solenoid controls a clutch member *m'*, for controlling the shipper cable *n* by which the switch 120 mechanism *o* is actuated from the car. 125

In the form of the invention shown in Fig. 4, I have illustrated the invention as applied to a door structure of the telescoping, counterweighted type, in which the two 130

door sections, a^2 and b^2 , have movement in parallel vertical planes and in the same direction, the opening and closing of the doors being facilitated by the counterweight p .
 5 In this form of the invention, the blocks i' upon the strip i instead of operatively engaging a hanger bar upon the doors, engage an extension p' upon the counterweights p . In other respects the construction of the controlling mechanism is the same as that shown in Figs. 1 and 2, it being understood, however, that the same manner of connecting the weight h with the door structure, might be employed in connection with an 10 elevator, using a shipper cable, by the modification of the make and break mechanism as shown in Fig. 3 and heretofore described.

In the form of the invention shown in Fig. 5, I have illustrated the application 20 of the invention to an elevator door of the laterally sliding type, this requiring merely the modification of the details in connecting the weight h with the door. The make and break mechanism is not illustrated in connection with this view, since a normally closed circuit, such as that shown in Figs. 1 and 2, or a normally open circuit, such as that shown in Fig. 3, may be used according to the type of elevator control employed.

30 In this form of the invention, I connect the strip or cable i with an endless strip q passing around suitable rollers r , r' , r^2 and r^3 , arranged in pairs at the top and at the bottom of the elevator shaft. Extending 35 from, and secured to, the reach q' of said endless strip q , are branch strips q^2 , extending about rollers s and s' at opposite sides of each door opening, to the reach q^3 upon the other side of the door openings, to which 40 they are secured. Said branch strip or cable passes through an opening in a bracket t carried by the door proper u , having a free sliding fit in said bracket, and is provided with a block v adapted to engage said 45 bracket.

Referring now to the form of the invention shown in Figs. 6 and 7, I have shown the invention as applied to double swinging elevator doors, this form of the invention like that shown in Fig. 5, requiring merely the modification of the connection between the weight h and the several doors in the shaft.

In this form of the invention, I employ a 55 strip q having the same general arrangement as illustrated in connection with Fig. 5, this strip being endless and passing about rollers r , r' , r^2 and r^3 . The reach q^3 is provided with blocks w^4 adapted to be engaged by rings w^3 carried by extension strips or cables w passing over the rollers w' , adjacent the door opening, and the roller w^2 carried by one of the swinging doors, x , and being connected with the other 60 swinging door x' of the pair. By this con-

struction it is impossible to open either swinging door section at any door opening without interrupting the circuit to the controller, or closing the circuit to the solenoid, according to the type of control which may 70 be employed.

The operation of the herein described device is substantially as follows:—

Referring more particularly to the form of the invention shown in Figs. 1 and 2 of the drawings, when all of the doors in an elevator shaft are closed, the weight h will, through the connecting strip or cable i , hold each of the blocks i' upon said strip or cable, in engagement with its associated hanger 80 bar b' of each of the doors in the shaft, the load of the weight h being applied to the stem f' in a manner to hold the bridge contact member f in engagement with the fixed contact members $e-e'$. Under this condition 85 the circuit to the controller E upon the car, will be closed so that power may be applied to the car at the will of the operator. When the car stops at any floor of the shaft, however, and the operator opens the door, as 90 the section a moves upwardly, the section b moves downwardly and the hanger bar b' thereon through its engagement with the block i' , raises the movable member or weight h by means of the connecting strip 95 or cable i carrying said block. With the ascent of said weight h , the spring f^3 will raise the stem f' and with it the movable contact member f , thus separating said contact from the contacts $e-e'$, to open the circuit to the controller E and prevent application of power to the car while the door 100 remains open.

The weight j is used in part as a counterweight to the weight h , and in part to hold 105 the strip or cable i taut, so that with the opening of one door, the blocks i' associated with the hanger bars of all other doors in a shaft, will move away from their associated hanger bars, and thus avoid the possibility of the fouling of said strip or cable.

Before the operator may apply power to the car, it is necessary to first close any open door, the closing movement of the door permitting the weight h to descend and causing the block i' associated with the hanger bar of the door being closed, to follow the hanger bar until the door is completely closed. When the door has been practically closed, each of the blocks i' will be in the 115 operative relation to its associated hanger bar.

As the weight h approaches the limit of its downward movement, it engages the stem f' which thereafter has movement with it 125 against the tension of the spring f^3 , until the movable bridge contact member f is in electrical connection with the fixed contact members $e-e'$.

The stem f' is slidably mounted in rela- 130

tion to the contact member f to permit movement of said stem in excess of that required to actually make contact with the members $e-e'$, thus compensating for irregularity in the movement of different doors in a shaft, or stretch in the strip or cable i .

The form of invention shown in Fig. 2, operates, as to the elevator doors, identically 10 as heretofore described. The sole difference between the operation of this form of invention and that shown in Figs. 1 and 2, being that with the ascent of the weight h , upon the opening of the door, the circuit is 15 made instead of being broken, and with the closing of the door the circuit is broken instead being made. When the circuit is closed the solenoid m is actuated to cause the clutch m' to grip the shipper cable n in 20 a manner to prevent its actuation, and when the circuit is open, the solenoid will be deenergized, thus permitting the clutch member m' to assume its normal inoperative relation to the cable so as to permit the actuation of said cable.

Referring now to the form of the invention shown in Fig. 4, the operation is identical with that heretofore described in connection with Figs. 1 and 2, the sole difference being that the weight h is actuated through the strip or cable i by the descent of the counterweight p instead of by the descent of the door itself.

The actuation of the make and break mechanism, in the form of the invention shown in Fig. 5, is identical with that heretofore described, this form of the invention differing from the form shown in Figs. 1 to 4, merely in the manner of actuating the weight h through the strip or cable i . When the door u is moved to the right in opening the door, the bracket t will exert a thrust upon the block v , which, through the branch strip or cable q^2 , will move the endless strip or cable q about the various pulleys r , r' , r^2 and r^3 . This movement of the strip or cable q will, through the strip or cable i , raise the weight. The movement of the endless strip or cable q will result from 45 the pull thereon from the branch strip or cable q^2 , thus causing an upward movement of the reach q' and a downward movement of the reach q^3 . During this movement the blocks v associated with other doors in the shaft, will move away from their cooperating brackets t .

Upon the closing of the door the weight h will impart such travel to the endless strip or cable q as to cause the block v of the open door to follow the door in its closing movement, and the blocks v upon other doors to resume their normal position in close juxtaposition to their cooperating brackets.

The operation of the form of the invention shown in Figs. 6 and 7 differs from

that of the form shown in Fig. 5 merely in the manner in which the door applies the actuating power to the strip or cable i .

In this form of the invention, if either door x or x' be open, it will exert a pull 70 upon the strip or cable w which, through the ring w^3 , will impart travel to the endless strip or cable q in a manner to raise the weight h . This results from the passing of the extension strip or cable w about the pulley w^2 upon one door and attaching the end thereof to the other door. With this construction it is impossible to move either door without exerting a pull upon said strip or cable w , and hence neither door can be 80 opened without developing conditions preventing the application of power to the car, according to the type of control employed. When the doors are open, the parts will be in the position indicated by the dotted lines 85 in Fig. 7.

When any door in the shaft is opened, the several blocks w^4 upon the endless strip or cable q associated with other doors, will move away from the ring w^3 of the branch 90 strip or cable w of that door.

As the door is closed, the stresses upon the endless strip or cable q will be relieved, thus permitting the weight h to descend and actuate the make and break mechanism in 95 a manner to permit the application of power to the car. The closing movement of the doors, will create slack in the extension strip or cable w , which slack will be taken up by the movement of the endless strip or cable q 100 during the movement thereof, imparted thereto by the weight h and the connection i .

It will be observed that in a controlling mechanism made in accordance with my invention, a single make and break mechanism 105 is used for controlling the circuit from which power for actuating the car is derived, and that this mechanism is operatively connected with each door in a shaft. In this manner the installation of the elevator 110 door equipment is very much simplified, and the make and break mechanism may be so positioned as to be inaccessible to the operator of the car, thus lending an additional factor of security in the elevator equipment. 115

The make and break mechanism, being controlled entirely by the movement of the doors, may be so set as to avoid any possibility of the application of power to the car, except when the door is closed. While the 120 strip or cable i is accessible to the car operator, it will be observed that it cannot be used by the operator in a manner to permit the application of power to the car so long as a door is open, since its movement, resulting in 125 the actuation of the make and break mechanism to permit application of the power is not possible without a closing movement of the door.

It is apparent that a controlling mecha- 130

nism made in accordance with my invention is not only capable of application to various types of elevator doors, but may be readily applied to different types of doors in the 5 same elevator shaft.

It is not my intention to limit the invention to the precise details of construction shown in the accompanying drawings, it 10 being apparent that such may be varied without departing from the spirit and scope 10 of the invention.

Having described the invention what I claim as new, and desire to have protected by Letters Patent, is:—

15 1. A controlling mechanism for elevator cars embodying therein a controller operative from within a car, a plurality of elevator doors in an elevator shaft, and means to prevent said controller being made operative to apply power to the car while any door is open, comprising an electric circuit, a single make and break mechanism arranged therein including a movable contact member, a slidable weight adapted, toward 20 the limit of its movement in one direction only, to engage said movable contact, springs acting upon said movable contact to normally thrust it toward said weight, a member having an opening therethrough carried 25 by each elevator door, a flexible strip connected with said weight and passing through the opening in each of said members, and a plurality of blocks carried by said strip, one adjacent each of said members, whereby said 30 weight will have movement in proportion to the quantity of movement of a door, and the initial opening movement of said door will permit movement of said contact under its spring, and with the completion of the closing movement 35 of said door said weight will operatively engage said contact, thus making said controller inoperative while any door is open, and permitting it to become operative only when a door is completely closed.

45 2. A controlling mechanism for elevator cars embodying therein a controller operative from within a car, a plurality of elevator doors in an elevator shaft, and means to prevent said controller being made operative to apply power to the car, comprising an electric circuit, including therein a plurality of fixed electric contacts, a movable bridge contact, adapted to coöperate therewith, a stem upon which said movable contact is slidably mounted, toward the limit of its movement in one direction only, a spring 50 acting upon said stem to normally thrust

said bridge contact toward said weight, a sliding weight adapted to operatively engage 60 said stem, a member having an opening therethrough carried by each elevator door, a strip connected with said weight and extending adjacent all of the doors in a shaft, and passing through the opening in each of 65 said members, and a plurality of blocks carried by said strip, one adjacent each of said members, whereby said weight will have movement in proportion to the quantity of movement of a door, and the initial opening 70 movement of said door will permit movement of said contact under its spring, and with the completion of the closing movement of said door said weight will operatively engage said contact, thus making said controller inoperative while any door is open, and permitting it to become operative only when a door is completely closed.

75 3. A controlling mechanism for elevator cars embodying therein a controller operative from within a car, a plurality of vertically sliding elevator doors moving in opposite directions in the same plane, the lower of said doors having a laterally extending hanger bar, and means to prevent said controller being made operative to apply power to the car, comprising an electric circuit, including therein a single make and break mechanism, a sliding weight adapted to operatively engage said make and break mechanism toward the limit of its movement in one direction only, said make and break mechanism including therein means whereby it will become automatically operative with 80 relation to said circuit substantially simultaneously with the disengagement of said weight therewith, a strip connected with said weight, passing through, and having a free sliding fit in an opening in the hanger bar in each door of a shaft, and a plurality of blocks carried by said strip in engageable relation with said hanger bars respectively, whereby said electric circuit will be 85 controlled to make said controller inoperative substantially simultaneously with the initial opening of the door, and to make it operative only with the complete closure 90 thereof.

100 In witness whereof I have hereunto affixed my signature, this 17th day of May, 1918, in the presence of two subscribing witnesses.

THOMAS NORRIS McNISH.
